UNITED STATES PATENT OFFICE

BALTUS ROLFS, OF WEST BEND, WISCONSIN

BILL FOLD, CARD CASE, AND THE LIKE

Application filed February 15, 1932. Serial No. 592,877.

This invention pertains generally to billfolds, card cases, and similar articles, wherein in it is desired to conveniently remove objects from the case.

5 The invention has primarily for its object to provide articles of the foregoing character with manually operable means for partially projecting articles from a pocket to facilitate selection and removal of the same.

10 Incidental to the foregoing, a more specific object resides in the provision of a case formed of soft, flexible material, such as leather and the like, having a relatively stiff container slidably mounted therein, and provided with 15 rigid means projecting through a slot in the case, whereby the container may be readily projected to expose the objects contained therein.

20 A more detailed object is to provide a structure of the foregoing character, in which the container is formed of "Celluloid", or similar material, and provided with a button rigidly secured thereto and projecting through a slot in the case to render the same readily accessible 25 for projecting the container.

25 A still further object resides in forming a 30 slideable container of relatively stiff material folded back upon itself, with one flap terminating short of the other so as to render objects retained therein readily accessible, and with the button or projection rigidly secured to the short flap.

35 With the above and other objects in view, which will appear as the description proceeds, the invention resides in the novel construction, combination and arrangement of parts, substantially as hereinafter described and more particularly defined by the appended 40 claim, it being understood that such changes in the precise embodiment of the herein disclosed invention may be made as come within the scope of the claim.

45 In the accompanying drawing is illustrated one complete example of the physical embodiment of the present invention constructed according to the best mode so far devised for the practical application of the principles thereof.

50 In the drawing:

Figure 1 is a perspective view of a conven-

tional structure of billfold in open position, with the present invention applied thereto, the container being shown in projected position.

Figure 2 is a similar view with the container retracted.

Figure 3 is a front elevation of the container, and

Figure 4 is a side elevation of the same.

While the present invention is illustrated in connection with a conventional structure of billfold, it is to be understood that the same is equally applicable to other devices, such as card cases, passbooks, cigarette cases, and the like, wherein the case is to be made of a soft, pliable material, such as leather or similar material.

In the illustration contained in the drawing, the numeral 1 designates a billfold provided with one or more pockets 2 on its inner side for reception of cards, passes, and similar flat objects. Inasmuch as considerable annoyance is encountered in selecting objects from the usual pocket, the present invention provides a container 3, preferably formed of relatively stiff material, such as celluloid or other composition, the same being slidably contained within the pocket 2.

As best shown in Figures 3 and 4, the container 3 is folded back upon itself, with its front flap 4 terminating short of the rear flap 5, thus rendering cards placed within the container readily accessible when the container is projected from the pocket 2.

To facilitate projection of the container from the pocket, the same has secured to its front flap 4 a button 6, the stem 7 of which projects through a longitudinal slot 8 formed in the inner wall 9 of the pocket. The head of the button is positioned outside 90 of the slot, where it is readily accessible for manual manipulation in projecting the container.

In the present instance, where the button is constructed of metal, the same is preferably riveted, or otherwise secured, to a small strip 10 of leather, or similar material, which in turn is stitched to the front flap 4 of the container. However, it is to be understood that any form of projection may 100

be utilized without in any way departing from the invention, which merely requires that some form of projection be rigidly carried by the container, and whether this is 5 formed integrally with the container or secured thereto, will in no way affect the principle of the invention.

In operation, cards, or the like, are placed 10 between the folds of the container, which is positioned within the pocket with its short flap towards the front of the same. In order to retract or project the container in the pocket, the same is readily accomplished by manipulation of the projection or button 6, 15 which is free to slide within the slot 8.

From the foregoing explanation, taken in 20 connection with the accompanying drawing, it will be seen that an exceedingly simple and inexpensive means has been provided for not 25 only facilitating the projection of cards or

other objects from a pocket, but which also serves to protect and maintain the objects in good condition.

I claim:—

The combination with a billfold, a card-case, or similar article, constructed of soft, pliable material, and including a pocket provided with a slot in one of its side walls, a container slidably mounted in said pocket and formed from a strip of relatively stiff material folded upon itself with one flap terminating short of the other, a flexible patch stitched to the outer face of the short flap, and a metal button comprising a restricted shank secured to said flexible patch and projecting through said slot, and a head carried by the outer end of said shank and projecting beyond the sides of said slot. 70 75 80 85
